US0D1045898S

(12) **United States Design Patent** (10) Patent No.: **US D1,045,898 S**
(45) Date of Patent: ** Oct. 8, 2024

(54) **DISPLAY SCREEN OR PORTION THEREOF
WITH GRAPHICAL USER INTERFACE**

(71) Applicant: **RITE-HITE HOLDING
CORPORATION**, Milwaukee, WI
(US)

(72) Inventors: **James C. Boerger**, Franksville, WI
(US); **Richard Mews**, Bonduel, WI
(US); **Kenneth C. Bowman**,
Cedarburg, WI (US)

(73) Assignee: **RITE-HITE HOLDING
CORPORATION**, Milwaukee, WI
(US)

(**) Term: **15 Years**

(21) Appl. No.: **29/851,487**

(22) Filed: **Aug. 29, 2022**

(57) **CLAIM**

The ornamental design for “display screen or portion thereof with graphical user interface,” as shown and described.

DESCRIPTION

The FIGURE is a front view of a display screen or portion thereof with graphical user interface, showing our new design.

The outer broken lines indicate a display screen or portion thereof and form no part of the claimed design. The other broken lines show portions of the graphical user interface that form no part of the claimed design. The stacked dot colon feature forms part of the claimed design as shown.
